DESIGN FOR AN INDICATING ROTOR CASE FOR GYRO VERTICALS

Robert Haskins, Jr., Garden City, and Clare E. Barkalow, Floral Park, N. Y., assignors to Sperry Gyroscope Company, Inc., a corporation of New York

Application July 31, 1943, Serial No. 110,809

Term of patent 7 years

(Cl. D52—1)

To all whom it may concern:

Be it known that we, Robert Haskins, Jr., and Clare E. Barkalow, citizens of the United States of America, residing at Garden City and Floral Park respectively, in the county of Nassau and State of New York, have invented a new, original, and ornamental Design for an Indicating Rotor Case for Gyro Verticals, of which the following is a specification, reference being had to the accompanying drawing, forming part thereof:

Fig. 1 is a top plan view of an indicating rotor case for gyro verticals showing our new design.

Fig. 2 is a bottom plan view thereof.

Fig. 3 is a side elevational view thereof, and Fig. 4 is a front elevational view thereof.

We claim:

The ornamental design for an indicating rotor case for gyro verticals, as shown.

ROBERT HASKINS, JR.

CLARE E. BARKALOW.
